LIFESAVING DEVICE

Simon G. Carroll, Barranquilla, Colombia

Application April 22, 1939, Serial No. 269,522

6 Claims.

(Cl. 9—14)

The invention relates to a lifesaving device and more particularly to a collapsible or foldable floating life carrier.

The primary object of the invention is the provision of a device of this character, wherein the construction thereof is such that when not in service will be in a collapsed or folded condition for the convenient storage thereof at selected places on board a vessel, ship or the like or at docks, wharves or other places for use in an emergency by the dropping of the same into a body of water so that a person overboard can be readily rescued, either by clinging to such device or climbing inside for carriage thereby.

Another object of the invention is the provision of a device of this character, wherein on the dropping of the same into a body of water it will automatically become extended and float so that persons overboard can readily become rescued to avoid drowning, the device being a float and is susceptible of carrying supplies for emergency aid to those rescued.

A further object of the invention is the provision of a device of this character, wherein the construction thereof is novel in its entirety and is susceptible of easy handling for storage thereof or for bringing it into use for lifesaving purposes.

A still further object of the invention is the provision of a device of this character, which is simple in construction, thoroughly reliable and efficacious in operation, susceptible of manual folding or collapsing and automatic extending, and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a plan view of a lifesaving device constructed in accordance with the invention and set up for use.

Figure 2 is a side view thereof.

Figure 3 is a sectional view taken on the line 3—3 of Figure 1 looking in the direction of the arrows.

Figure 4 is a sectional view taken on the line 4—4 of Figure 1 looking in the direction of the arrows.

Figure 5 is a plan view of the device when collapsed or folded.

Figure 6 is a side elevation thereof in folded or collapsed condition.

Similar reference characters indicate corresponding parts throughout the several views in the drawings.

Referring to the drawings in detail, A designates generally the device in its entirety constructed in accordance with the invention and comprises a foraminous carrier body formed with four side walls, a drop bottom, being open at 10 its top, and peripherally about this body next to its open top is a continuous laterally outstanding bridge. Each of the side walls involves a metal frame 10 preferably made from piping and metallic wire mesh covering 11, the frames 10 being 15 hingedly connected to each other preferably through loose linkage 12 so that the side walls can be brought together or extended at right angles to each other in the folding or collapsing and in the setup of the carrier.

The drop bottom comprises a frame 13 made from piping, having a metal wire mesh covering 14 and is vertically swingable, being hinged to the lowermost portion of one side of the carrier, the hinge connection being linkage 15. The lead edge of the drop bottom, which is the edge of the frame 13 opposite the hingedly connected edge with the side wall, has provided thereon keepers 16 engageable with the lowermost portion of the side wall adjacent to the lead edge 20 of the bottom when closed. This drop bottom by gravity lowers from a raised or elevated position to a closing position, the elevated or raised position being the normal disposition thereof, particularly when the side walls are folded or collapsed and such bottom in its movement swings within the four walls of the carrier.

The bridge comprises the oppositely disposed swingable long and short frames 17 and 18, respectively, each having wire mesh coverings 19 40 and these constitute the flooring to the bridge, the frames being normally disconnected from each other and are hinged to the side walls of the carrier by linkage 20 so that the same will not interfere with the collapsing or folding of 45 the body of the carrier constituted by said four walls before mentioned. Swingably connected to the frames 17 and 18 are guard frames 21, each having a wire mesh covering 22 and said frames 21 are hinged to the frames 17 and 18 by linkage 23. The frames 21 are normally disconnected 50 from each other so as not to interfere with the folding or collapsing of the side walls of the body of the carrier.

The side wall frames 10 immediately beneath 55

the bridge of the carrier are formed with insets 24 creating pockets for inverted substantially conical shaped buoyant elements 25, these being suitably loosely connected with said frames 10 and the frames 21 at 26 and 27, respectively, so that when the side walls of the body of the carrier are collapsed or folded the said buoyant elements 25 will not interfere therewith, being swung clear from within the pockets for said elements, as is clearly shown in Figures 5 and 6 of the drawings. Now when the carrier is extended or automatically sets itself up for use, the buoyant elements 25 move within the pockets therefor, as is clearly shown in Figures 1, 2, 3 and 4 of said drawings. In this position of the buoyant elements 25, the floor of the bridge rests upon the tops of said elements while the guard frames at their ends adjacent to each other for the holding of the said guard frames in an upright or perpendicular position can be separably fastened together, as at 28. The side walls of the body of the carrier at their uppermost portions constitute an inside guard railing for the bridge when the carrier is extended or set up for use.

25. By reason of the construction of the bridge and the adjunct swinging connections thereof with the side walls of the body of the carrier, the said bridge can be brought to a folded or collapsed condition simultaneously with the folding or collapsing of the said body of the carrier, the folded condition of the carrier in its entirety being illustrated in Figures 5 and 6 of the drawings, and such is the normal condition thereof. The carrier, when folded or collapsed, can be readily dropped in this condition into a body of water and on dropping therein the side walls will automatically become extended and by gravity the bottom lowers to a closed position. The floor of the bridge can be swung outwardly with respect to the side walls of the body of the carrier to a rest position on the buoyant elements 25 and the guards of the bridge brought to an upright position with the meeting ends of these separably fastened together, as at 28, resulting in the setting up of the bridge. There is no liability of the folding or collapsing of the carrier when afloat in a body of water because the bottom in its closed position eliminates this possibility. The carrier when afloat serves as a lifesaver in that persons overboard can clutch the carrier and by holding on be prevented from drowning or such persons can climb into the carrier and in this manner be held afloat or against sinking until relief is brought to such rescued persons.

55. The device is non-capsizing and maintains rescued persons thereby from drowning and afloat until relief is had.

It is of course understood that the frames 21 of the bridge necessarily must be detached from each other at their meeting ends before the collapsing or folding of the carrier can be accomplished and these frames 21 as well as the frames 17 and 18 are brought to a folded relationship to each other in conjunction to the folding or collapsing of the side walls of the body of the carrier, being clearly illustrated in Figures 5 and 6 of the drawings.

The bridge of the carrier facilitates persons standing thereon of effecting rescue work to others in the water, particularly aiding in the bringing of the rescued persons into the carrier.

The buoyant elements 25 sustain the carrier afloat in a body of water irrespective of the turbulence of such body of water and in the loading of 75 such carrier for carrying forth rescue work, it

will not become capsized even if weight is shifted from one side to the other, the carrier having the buoyant elements distributed at four points thereof.

What is claimed is:

1. A lifesaving device comprising a reticulated extensible and collapsible body having recessed corner formations, a bridge peripherally about the uppermost portion of said body above the recessed corner formations and extensible and collapsible therewith, and buoyant elements carried by the body and flexibly connected thereto for movement into and out of the recessed corner formations and constituting supports for the bridge when extended. 5

2. A lifesaving device comprising a reticulated extensible and collapsible body having recessed corner formations, a bridge peripherally about the uppermost portion of said body above the recessed corner formations and extensible and collapsible therewith, buoyant elements carried by the body and flexibly connected thereto for movement into and out of the recessed corner formations and constituting supports for the bridge when extended, and means for holding the bridge 20 in an extended condition when the body has been extended. 25

3. A lifesaving device comprising a reticulated extensible and collapsible body having recessed corner formations, a bridge peripherally about the uppermost portion of said body above the recessed corner formations and extensible and collapsible therewith, buoyant elements carried by the body and flexibly connected thereto for movement into and out of the recessed corner 30 formations and constituting supports for the bridge when extended, and means for holding the bridge in an extended condition when the body has been extended, the said body being entirely open at its upper portion and having its walls 35 extended upwardly with relation to the bridge. 40

4. A lifesaving device comprising a reticulated extensible and collapsible body having recessed corner formations, a bridge peripherally about the uppermost portion of said body above the recessed corner formations and extensible and collapsible therewith, buoyant elements carried by the body and flexibly connected thereto for movement into and out of the recessed corner 45 formations and constituting supports for the bridge when extended, means for holding the bridge in an extended condition when the body has been extended; the said body being entirely open at its uppermost portion and having its walls 50 extended upwardly with relation to the bridge. 55

5. A lifesaving device comprising a reticulated extensible and collapsible body having recessed corner formations for buoyant elements, an extensible bridge peripherally about the uppermost 60 portion of said body above the recessed corner formations and extensible and collapsible therewith, buoyant elements carried by the body and flexibly connected thereto for movement into and out of the recessed corner formations and constituting supports for the bridge when extended, means for holding the bridge in an extended condition when the body has been extended, the said body being entirely open at its uppermost portion and having its walls 65 extended upwardly with relation to the bridge, framings for the body and bridge, and a reticulated flexible bottom for said body. 70

6. A lifesaving device comprising a reticulated extensible and collapsible body having recessed cor- 75

ner formations for buoyant elements, an extensible bridge peripherally about the uppermost portion of said body above the recessed corner formations and extensible and collapsible therewith, buoyant elements carried by the body and flexibly connected thereto for movement into and out of the recessed corner formations and constituting supports for the bridge when extended, means for holding the bridge in an extended condition when

the body has been extended, the said body being entirely open at its uppermost portion and having its walls extended upwardly with relation to the bridge, framings for the body and bridge, a reticulated flexible bottom for said body, said body having foldable sides, and hinge connections between said sides. 5
